UNITED STATES PATENT OFFICE.

CHARLES T. RAY, OF LOUISVILLE, KENTUCKY, ASSIGNOR TO B. F. AVERY & SONS, OF LOUISVILLE, KENTUCKY, A CORPORATION OF KENTUCKY.

CULTIVATOR.

1,280,545.

Specification of Letters Patent.

Patented Oct. 1, 1918.

Application filed October 9, 1917. Serial No. 195,572.

To all whom it may concern:

Be it known that I, CHARLES T. RAY, a citizen of the United States, residing at Louisville, in the county of Jefferson and State of Kentucky, have invented certain new and useful Improvements in Cultivators, of which the following is a specification.

This invention relates to riding cultivators and has for one of its most important objects the provision of a cultivator whose beams which carry the tillage elements are mounted to have vertical and lateral movements and whose seat is similarly mounted to have vertical and lateral movements and is so connected with the beams that the vertical and lateral movements of the beams are controlled by corresponding movement of the seat. It further has for one of its most important purposes a correlation of beams which are movable sidewise and up and down and a seat mounted to have movement on vertical and horizontal axes for controlling said movements of the beams, wherein either beam may be moved up or down relatively to the other without destroying or substantially reducing the balance between either beam and the weight of the operator.

It will thus be seen that one of the most important purposes of the present invention is to provide a riding cultivator in which will be combined the advantages of the cultivators commonly known in the trade as "leverless" and also the advantages of the cultivators commonly known in the trade as "pivoted seat guide" or "wiggle tail".

A still further purpose of the invention is to provide a cultivator having the combined advantages hereinbefore set forth and which will moreover be of very simple construction and in which the seat may be moved in the directions for transmitting the aforesaid up and down and lateral movements to the beams with the expenditure of a minimum amount of force.

The foregoing purposes and others which will hereinafter appear are secured from the constructions illustrated in the accompanying drawings and in which drawings:

Figure 1 is a plan view of a riding cultivator exemplifying the preferred embodiment of the present improvements, the gang beams and adjunctive parts at one side being

omitted because they are duplicates of the corresponding parts at the other side. 55

Fig. 2 is a side elevation.

Fig. 3 is a rear view of a part of the rear arch and shows thereon the preferred means by which the seat support is mounted to have movement upon vertical and horizontal 60 axes and the means by which the same is connected to the beams for transmitting up and down movement to the latter and maintaining balance between the beams and the weight of the operator. 65

Fig. 4 is a detail view of one end of the equalizer particularly showing the correlation of the same with a member of the connection of the corresponding beam.

Figs. 5 and 6 are detail representations of 70 modified forms of means to take the place of the elements shown in Figs. 3 and 4.

Figs. 7 and 8 are detail representations showing the preferred form of connection between the front end of the seat support 75 and the rear end of the pole: Fig. 7 being a plan view of the connection and Fig. 8 a side view of the same.

Figs. 9 and 10 are detail representations of another form of such connection which 80 may be used in lieu of the form shown in Figs. 7 and 8.

Similar characters of reference denote corresponding parts in the several views.

The frame of the cultivator selected to 85 exemplify the present invention is formed of two side members marked 10 and 11 respectively, having their forward ends connected with each other by a box 12 and diverging thence to a point near their rear ends from which point they extend in substantially parallel planes for an appropriate distance and are connected with each other at their rear ends by a fixed tube 13. The frame also includes a transverse brace 14 90 between its ends.

15 designates the opposite arch sections constituting the rear axle, having outwardly extending spindles 16 upon which the wheels 17 are journaled. The upper portion of 100 these arched sections are journaled in the fixed tubular frame member 13. The arch is made of separated sections to permit the wheels to be adjusted in or out, as is well known, and any suitable means are provided 105 for holding them in their adjusted position.

18 designates a front arch having outwardly extending lower ends and to these outwardly extending ends 19 the front ends 5 of gang beams 20 are connected by the usual or any suitable means providing for vertical and horizontal pivotal movements of the beams or gangs with relation to the arch. These connections generally include sleeves 21 pivoted to turn upon the ends 19 and 10 couplings 22 secured to the front ends of the beams and having vertical pivots 22^a connecting them with the sleeves. In lieu of using the hobbles commonly used for fixing the gang beams in various selected distances 15 apart, I prefer to employ braces 23 which extend rearwardly and inwardly from the respective sleeves 21 to lugs or ears 24 to which they are connected by lock nuts 25 threaded upon the rear end of the braces 20 23 and engaging opposite sides of the ears. It will be understood that the gangs may be adjusted in or out by adjusting the nuts 25.

This front arch is journaled in a bearing 26 which is pivotally connected at 27 between upper and lower straps 28 and 29. These straps at their forward ends are rigidly secured to the rear end of the pole 30 and this pole is pivoted at 31 in the box 12. The front arch is connected to the frame 30 by the rearwardly and upwardly inclined rods 32 and is further connected with the frame by vertical rods 33.

34 designates the seat. This seat is mounted upon a suitable support, preferably 35 formed of spaced longitudinal side members 35. The seat support is essentially so mounted and so connected with the beams, as already stated, that the lateral guidance 40 of the beams and their up and down movements may be controlled by the seat, and hence it is characterized by being mounted to have movement upon both vertical and horizontal axes, its movement upon either axis being at the will of the operator and 45 its connections with the beams being such that its movement upon the horizontal axis will lower the seat and raise the beams or raise the seat and lower the beams, according to the direction of such movement, while its 50 movement upon the vertical axis will move the beam sidewise, to the right or left, according to the direction of the movement of the seat, the sidewise movement of the beams being toward the right when the seat is 55 moved toward the left and toward the left when the seat is moved toward the right. The means by which the important end of controlling both the lateral guidance of the beams and their up and down movements 60 by the seat is further characterized in the illustrated embodiments of the invention by elements or correlation of parts which afford facilities for the up and down movements of either beam relatively to the other and at 65 the same time maintain the balance between

the beams and the weight of the operator. The preferred means for the several purposes referred to are as follows:

In the form shown in Figs. 1-4 inclusive and 7 and 8 there is a sleeve 36 having a 70 vertical pivot 37 about midway of its length and arms 38 and 39 near its opposite ends. This sleeve is journaled to rotate upon the fixed tubular frame member 13. Between the forward ends of the members 35 constituting the seat support, when such spaced members are used, there is a filling block 40 having an opening 41 which receives the pivot 37 and constitutes a bearing therefor. The seat bar is preferably braced by a member 42 which extends longitudinally thereof and has its forward end pivoted to the upper end of a member 43 which rises from the sleeve 36 and is arranged in vertical alignment with the pivot 37. It will thus be 80 seen that the seat support is movable upon a vertical axis about the pivots 37 and 43 and similarly is movable upon a horizontal axis by the rotative movement of the sleeve 36 about the tubular frame member 13. 90

The arms 38 and 39 extend forward from the sleeve 36 and are connected with the respective beams 20 by suitable means as flexible chains 44 and 45 for example. These chains are preferred because they not only 95 are flexible but further permit the convenient adjustment of the length thereof to set the beams at different heights with relation to the seat. The upper ends of these chains are provided with hooks 44^a and 45^a by which 100 they are connected to the respective arms 38 and 39 and these arms are respectively formed with a series of openings 38^a and 39^a extending longitudinally thereof, any one of which is adapted to receive the upper end of 105 the adjacent hook. This permits adjustment of the connections between the arms and the beams in the direction of the length of the arms to vary the leverage to bring about a proper balance between the weight of the 110 operator and the weight of the beams. Similar adjustments of the lower ends of the chains are afforded at the beams by providing a series of openings to receive appropriate elements, as hooks or bolts, carried 115 by the lower ends of the chain. These openings are indicated at 44^b and 45^b in Figs. 2 and 1 respectively and upon reference to Fig. 1 it will be apparent that they are formed in brackets secured to the beam, these 120 brackets being marked 45^c. This adjustment of the beams supplements the adjustment of the arms and the two co-acting to make it possible to bring about a perfect balance throughout a maximum range of weights of 125 operators.

The arms 38 and 39 are provided with rearward projections 46 and 47 and these rearward projections are engaged by the opposite ends of an equalizer 48, which 130

equalizer is carried by the sleeve 36 and is pivoted between its ends whereby it partakes of the axial movement of the sleeve about the tubular frame member 13 and is 5 also movable pivotally relatively to the sleeve. This correlation of sleeve, equalizer and arms enables either beam to be raised or lowered relatively to the other and at the same time maintains perfect balance between the beams and the weight of the operator at all times. When the sleeve 36 is turned upon its horizontal axis with the up or down movements of the seat the equalizer moves bodily forward or backward there- 10 with and if at this time the foot pressure upon both beams be relaxed the beams will move simultaneously upward when the seat is moved downward. In this case the equalizer moves bodily with the sleeve which 15 latter turns in a backward direction upon the frame member 13, the movement of the equalizer however, being toward the front of the implement and the arms 38 and 39 moving upward and rearward. When it is 20 desired to raise one beam only, the foot pressure upon the beam to be elevated is relaxed while the other beam is held by foot pressure. When the seat descends the sleeve rotates as before and the arm 38 or 25 39 connected with the unrestrained beam will move upward and backward. In this case the equalizer while it is carried forward with the rotating movement of the sleeve is not carried forward bodily, as before, for 30 the reason that its end engaged with the arm which is connected to the restrained beam is held against movement and hence the forward movement of the sleeve now communicates pivotal movement to the equal- 35 izer, the fulcrum of the equalizer being at the end adjacent to the restrained beam and arms. The result of this correlation of parts is that the balance between the weight of the operator and both beams is maintained notwithstanding the movement of one beam.

It will be noted that the particular form of this part of the implement shown in Fig. 3 embodies a continuous sleeve 36 having the arms 38 and 39 near its opposite ends. 40 In such case these arms should have pivotal movement relatively to the sleeve and hence the sleeve is provided at one end with a pair of spaced ears 36^a to which the arm 38 is pivoted at 38^b and near its opposite end 45 with a similar pair of spaced ears 36^b to which the arm 39 is pivoted at 39^b. It is necessary only however, that the equalizer partake of the pivotal movement of the seat and seat support about the horizontal axis 50 of the latter and be capable of transmitting movement therefrom to either of the arms 38 and 39 at the will of the operator, and that these arms 38 and 39 be mounted to move upon horizontal axes either together 55 or relatively to each other in accord with

the movements of the beams and seat and seat support, the movement of the equalizer when transmitting movement to either arm being a pivotal one with its fulcrum adjacent to the arm which is being held. Various specifically different embodiments including such correlation of parts, in addition to the one already particularly described, will suggest themselves and are contemplated to be within the spirit of the invention and the scope of the claims. Thus in Fig. 5 the sleeve is divided into three separate sections marked 36^w, 36^x, and 36^y, the sections 36^x and 36^y being rotative upon the tubular frame member 13 relatively to each other and relatively to the intermediate section 36^w, the latter section carrying the pivots for the seat support and equalizer. In this particular form the arms, which are marked 38^y and 39^x, are integral with the sleeve sections 36^x and 36^y respectively, instead of being pivotally connected therewith. The intermediate section 36^w carries the pivots for the seat support and to it the equalizer 48 is pivoted between its ends precisely as in the form shown in Fig. 3. In both of the hereinbefore described typical embodiments the equalizer is pivoted between its ends upon the vertical pivot 37 but this is not necessary as it may be pivoted upon a horizontal pivot, for example, with equally good results as exemplified by Fig. 6. This pivot is marked 37^z and as shown extends rearward from the sleeve 36^z, this sleeve being in this particular form preferably continuous as is the sleeve 36 shown in Fig. 3 and hence the arms, marked 38^y and 39^y, are shown as being pivotally connected to opposite ends of the sleeve 46^y and 47^y but instead of extending below the sleeve as in Fig. 3 extend around the upper surface of said sleeve. Obviously an equalizer mounted on such a horizontal pivot might be correlated with arms carried by separate sleeve sections, such for example as shown in Fig. 5.

The front end of the seat support 35 is connected with the rear end of the pole 30 by means which is of a nature such that it will transmit sidewise movement to the pole and cause the latter to turn on its vertical pivot when the seat support is turned upon its vertical pivot and will be operatively connected to the pole for such movement only. Many suitable connections having these characteristics will suggest themselves and some of the same are shown in the drawings for exemplary purposes. I prefer the one shown best in Figs. 7 and 8. This comprises a member 49 whose front end is connected with the rear end of the strap 29 by a vertical pivot 50, adapted to traverse a slot 51 in said strap and whose rear end is connected to the front end of the seat support by a horizontal pivot 52. When

the seat and seat support are moved on their vertical axis toward the right or the left the member 49 moves therewith about the pivot 50 as a fulcrum and this pivot 50 communicates movement to the rear end of the pole in the direction opposite the direction of movement of the seat support. When the seat support is moved up or down on its horizontal axis it turns relatively to the 10 member 49 by reason of the provision of the horizontal pivot 52 and this member 49 in this case moves bodily, without communicating any movement to the pole. The same results are secured from the construction exemplified in Fig. 9 wherein the front end of 15 the seat support is formed to provide forwardly projecting arms marked 53 and 53^a arranged on opposite sides of a pivot 54 carried by the rear ends of upper and lower 20 straps 55 and 55^a. The arms 53 and 53^a in this case are fixedly secured to the seat support and in practice may be integral therewith. It is apparent that when the seat support is moved on its vertical pivot, movement 25 will be transmitted to the straps 55 and 55^a and hence to the rear end of the pole as before described and that when the seat support is moved upon its horizontal pivot the arms 53 will move relatively to the pivot 54 30 without communicating any movement to the pole, it being understood of course that the distance between the straps 55 and 55^a is equal to the maximum extent of movement of the arms 53 about the horizontal 35 axis.

The wheels are adjustable forward or rearward in accord with the weight of the operator to give the implement proper balance and are held in their adjusted positions 40 by arms, one of which is shown in Fig. 2 and is designated 56. This arm has its front end pivoted at 56^a to a projection 57 extending from the sleeve 21 and its rear end is provided with a series of downwardly open 45 notches 58, any one of which is adapted to engage a pin 59 shown dotted in Fig. 2 and is held against rising from said pin by a pivoted cam 60.

Having now described the construction 50 selected to exemplify the present invention but to the details of which the invention is not in all respects restricted it will be apparent that the operation will be as follows:

The wheels are adjusted to suit the weight 55 of the operator and are fixed in adjusted position by the arms 56 the rear arched axle moving forward or backward in the bearings in the frame during this adjustment as usual. The height of the seat is 60 varied initially in accord with the depth of cultivation by shortening or lengthening the chains 44 and 45 and these chains are connected to the particular openings 38^a and 39^a in the respective arms 38 and 39 selected

in accord with the weight of the operator 65 and to give a proper balance between the operator and the beams. In the operation of cultivating the operator places his feet in stirrups upon the beams as usual, one of said stirrups being shown in Fig. 2 and 70 marked 61, and the beams may also be provided with handles 62 which supplement the stirrups in the handling of the beams. The initial adjustment to bring about a proper balance between the beams and the 75 weight of the operator is preferably such that the beams may be caused to penetrate the soil and be held in their proper position for operation without the exercise of any undue foot pressure by the operator and 80 with the seat in substantially horizontal position and yet make the beams and seat responsive to any relaxation of the pressure upon either beam. It will be understood that the beams are pressed into the soil by 85 pressure applied on the stirrup supplemented if need be by pressure applied to the handles. When for any purpose it is desired to move the beams laterally in following the row, the operator moves his body and 90 consequently the seat and seat support toward the side opposite that to which he wishes the beams to go. This moves the pole pivotally and carries the front arch and the front end of the frame toward the 95 side selected and thereby causes the wheels to angle. When it is desired to elevate both of the beams simultaneously, as at the end of the row, or when transporting the implement to the field to be cultivated, the operator relaxes the pressure upon both beams at the same time thereby transferring his entire weight to the seat which descends and lifts both beams, at the same time, the 100 equalizer moving bodily with the sleeve and arms and causing the arms to move evenly and simultaneously. When it is desired to lift one beam to free it of obstructions and continue to cultivate with the other beam, the operator relaxes the pressure on the beam 105 to be raised and continues pressure upon the other beam. The seat is permitted to descend by the weight of the operator and its descent causes the sleeve 36 or 36^a, or the sleeve section 36^w and one of the sleeve sections 36^x or 36^y—according to which form is embodied in the implement—to rotate 110 slightly upon the horizontal axis about the tubular frame member 13 and carries the equalizer with it. As one of the arms is 115 stationary in this movement the equalizer is moved pivotally, its fulcrum being at the held arm and it communicates movement to the other arm, thereby lifting the gang from which the foot pressure has been removed. 120 It will be understood that in the guidance of the cultivator by shifting the pole pivotally and angling the wheels the front arch 125

moves laterally with the pole thus moving the beams laterally. If however, it is desired to provide for independent lateral movement of the beams and to make them laterally movable relatively to the arch, the front ends of the braces 23 may be disconnected from the sleeve 19. When this has been done the beams may be freely swung laterally on their vertical pivots 22^a.

10 Having thus described the invention what I believe to be new and desire to secure by Letters Patent, and what I, therefore, claim is:—

15 1. In a cultivator, the combination with a frame, a seat, and beams which are movable sidewise and up and down relatively to the frame, of means for controlling said movements of the beams by corresponding movements of the seat, including a seat support having movement on vertical and horizontal axes and connections for transmitting movements between the seat support and the beams.

20 2. In a cultivator, the combination of a frame, a pivoted pole, beams which are movable sidewise and up and down relatively to the frame, connections between the beams and the pole, a seat, a seat support having movement on vertical and horizontal axes, and connections between the seat support and the pole and beams to control the lateral guidance of the beams and their up and down movements by the seat.

25 3. In a cultivator, the combination of a wheeled frame, a pole pivoted thereto, a laterally movable front arch, a pivotal connection between the pole and front arch, beams suspended at their forward ends from the ends of the front arch, and having movement on horizontal axes relatively thereto, a seat, a seat support mounted to have movement relatively to the frame on both horizontal and vertical axes, and connections between the seat support and the pole and beams to control the lateral guidance of the beams and their up and down movements by the seat.

30 4. In a cultivator, the combination of a frame, beams which are movable sidewise and up and down relatively to the frame, a seat and means for controlling the sidewise guidance of the beams and their up and down movements by the seat, including a seat support having movement on both horizontal and vertical axes, connections between the seat support and beams, a pole pivoted to the frame to move on a vertical axis relatively thereto, connections between the pole and beams, a connection between the forward end of the seat support and the rear end of the pole, said connection being movable sidewise with the seat support about the vertical axis of the latter to transmit movement to the pole and being operatively connected with the rear end of the pole for

such movement only, to permit movement of the seat support on its horizontal axis without affecting the pole.

5. In a cultivator, the combination of a frame, beams which are movable sidewise and up and down relatively to the frame, a seat, a seat support having movement in both horizontal and vertical axes, connections between the seat support and beams, a pole pivoted to the frame to move on a vertical axis relatively thereto, connections between the pole and beams, and means between the seat support and the pole, for transmitting movement from one to the other on their vertical axes, and having a lost motion connection at one end to permit movement of the seat support on its horizontal axis relatively to the pole.

10 6. In a cultivator, the combination of a frame, beams which are movable sidewise and up and down relative to the frame, a seat and means for controlling the sidewise guidance of the beams and their up and down movements by the seat, including a seat support having movement on both vertical and horizontal axes, connections between the seat support and the beams, a pole pivoted to the frame on a vertical axis, and a lost motion connection between the pole and the seat support, including a vertical pivot through which movement of the seat support on its vertical axis only is transmitted to the pole, and connections between the pole and beams.

15 7. In a cultivator, the combination of a frame, beams which are movable sidewise and up and down relatively to the frame, a seat and means for controlling the sidewise guidance of the beams and their up and down movements by the seat, including a seat support having movement on both horizontal and vertical axes, connections between the seat support and the beams, a pole pivoted to the frame on a vertical axis, a member having one end connected to the seat support by a horizontal pivot and its other end connected to the pole by a vertical pivot and connections between the pole and beams.

20 8. In a cultivator, the combination of a frame, beams which are movable sidewise and up and down relatively to the frame, a seat and means for controlling the sidewise guidance of the beams and their up and down movements by the seat, including a seat support having movement on both horizontal and vertical axes, connections between the seat support and the beams, a pole pivoted to the frame on a vertical axis, a member having one end connected to the seat support by a horizontal pivot and its other end connected to the pole by a vertical pivot, one of said pivots having a lost motion connection with the adjacent part, and connections between the pole and beams.

9. In a cultivator, the combination of a frame, beams which are movable sidewise and up and down relatively to the frame, a seat and means for controlling the sidewise guidance of the beams and their up and down movements by the seat, including a seat support having movement on both horizontal and vertical axes, connections between the seat support and the beams, a pole pivoted 10 to the frame on a vertical axis, a member for transmitting movement on vertical axes only between the pole and seat support, said member having a horizontal pivot connecting one of its ends with the seat support and a vertical pivot connecting its other end with the pole, the part engaged by one of said pivots having a slot which is traversed by the pivot.
10. In a cultivator, the combination with a frame, a seat, and beams which are movable 20 up and down relatively to each other, of means for controlling said movements of the beams by corresponding movements of the seat, including a seat support having movement on a horizontal axis relatively to the 25 frame, an equalizer which bodily partakes of said movement of the seat support and is pivoted between its ends, pivoted arms, and connections between the arms and the respective beams, said equalizer having its ends 30 connected to said arms and being movable on its pivot for transmitting movement from either arm to the other.
11. In a cultivator, the combination with a frame, a seat, and beams which are movable 35 up and down relatively to each other, of means for controlling said movements of the beams by corresponding movements of the seat, including a seat support having movement on a horizontal axis relatively to the 40 frame, an equalizer which bodily partakes of said movement of the seat support and is pivoted between its ends, forwardly extending pivoted arms each having a plurality of openings, and connections between the arms 45 and the beams adapted to engage either of the openings, said equalizer having its ends engaging said arms and being movable on its pivot for transmitting movement from either arm to the other.
12. In a cultivator, the combination with a frame, a seat, and beams which are movable 50 up and down relatively to each other and each having a plurality of openings spaced along the length thereof, pivoted arms each 55 having a plurality of openings, and connections between the arms and beams, selectively adapted to the openings in the same, of a seat, a support for the seat, movable upon a horizontal axis, and an equalizer movable 60 bodily with the seat support and pivoted between its ends and having its ends engaging the arms.
13. In a cultivator, the combination with a frame, a seat, and beams which are movable 65 up and down relatively to each other, of a

sleeve mounted to rotate upon a horizontal axis and connected to the seat support, arms pivotally connected to said sleeve, connections between said arms and the respective beams, and an equalizer pivoted between its 70 ends to the sleeve and having its ends engaging the arms.

14. In a cultivator, the combination with a frame, a seat, and beams which are movable 75 up and down relatively to each other, of a sleeve mounted to rotate upon a horizontal axis and connected to the seat support, a pair of arms pivotally connected with the sleeve and having forwardly and rearwardly projecting portions, means connecting the forwardly projecting portions to the respective beams, and an equalizer pivoted between its 80 ends to the sleeve and having its ends seated against the rearwardly projecting portions of the arms.

15. In a cultivator, the combination with a frame, a seat and beams which are movable up and down and sidewise relatively to the frame, of means for controlling said movements of the beams by corresponding movements of the seat, including a seat support having movement on vertical and horizontal axes, arms each pivoted to move upon a horizontal axis, an equalizer which partakes bodily of the movement of the seat support 90 on the horizontal axis and is pivoted between its ends and has its ends engaging the arms to transmit movement from one to the other, connections between the arms and the respective beams for moving the same up or down 100 relatively to each other and separate connections between the seat support and the beams for moving the latter sidewise.

16. In a cultivator, the combination with a frame, a seat and beams which are movable up and down and sidewise relatively to the frame, of means for controlling said movements of the beams by corresponding movements of the seat, including a sleeve movable upon a horizontal axis, a seat support pivoted upon a vertical axis to the sleeve, arms pivoted upon horizontal axes to the sleeve and projecting therefrom, connections between the arms and the respective beams, an equalizer pivoted between its ends 115 to the sleeve and having its ends engaged between the arms to transmit movement from one to the other and separate connections between the seat support and the beams for transmitting sidewise movement to the latter when the seat support is turned relative to the sleeve upon its vertical axis.

17. In a cultivator, the combination with a frame, a seat, and beams which are movable sidewise and up and down relatively to the frame, of means for controlling said movements of the beams by corresponding movements of the seat, including a seat support having movement upon horizontal and vertical axes, an equalizer which bodily 130

partakes of said movement of the seat support and is pivoted between its ends, arms pivoted upon horizontal axes and engaged by the ends of the equalizer, connections between the said arms and the respective beams, a pole pivoted upon a vertical axis, connections between said pole and the beams, and means connecting the forward end of the seat support with the rear end of the 10 pole for transmitting movement of the seat support on its vertical axis to the pole.

18. In a cultivator, the combination with a frame, a seat, and beams which are movable up and down relatively to each other, of 15 an equalizer and means for connecting the seat, the equalizer and the beams in such manner that when one beam is released and the other held, the movement of the seat moves the released beam through the action 20 of the equalizer, said equalizer acting under the movement of the seat against the held beam to impart movement to the released beam.

19. In a cultivator, the combination with 25 a frame, a seat and beams which are movable sidewise and up and down relatively to the frame, of means for controlling said movements of the beams by corresponding movements of the seat, including a seat support having movement on vertical and horizontal axes, connections between said support and the beams for transmitting movement to the beams from the support, said 30 connections including elements by which the beams are mounted for vertical pivotal movement, and rigid braces extending between said elements and the beams to hold said beams in definite angular relation to said elements.

40 20. In a cultivator, the combination with a frame, a seat and beams which are movable sidewise and up and down relatively to the frame, of means for controlling said movements of the beams by corresponding movements of the seat, including a seat support 45 having movement on vertical and horizontal axes, connections between said support and the beams for transmitting movement to the beams from the support, said connections in-

cluding sleeves mounted to turn upon horizontal axes, connections between the sleeves and the beams for mounting the beams to swing horizontally with respect to the sleeves and rigid braces extending between the sleeves and the beams to hold the beams in 55 definite angular relation to the sleeves.

21. In a cultivator, the combination with a frame, a seat and beams which are movable sidewise and up and down relatively to the frame, of means for controlling said 60 movements of the beams by corresponding movements of the seat, including a seat support having movement on vertical and horizontal axes, connections between said support and the beams for transmitting movement to the beams from the support, said 65 connections including sleeves mounted to turn upon horizontal axes, connections between the sleeves and the beams for mounting the beams to swing horizontally with 70 respect to the sleeves, braces, one end of each of which is connected to the corresponding sleeve and the opposite ends of which are threaded, members carried by the beams through which said threaded ends pass and 75 nuts upon said ends for binding said braces into rigid relation to said beams.

22. In a cultivator, the combination of a wheeled frame, a pole pivoted thereo, a laterally movable front arch having outturned 80 ends, a pivotal connection between the pole and front arch, sleeves on the outturned ends of the arch and movable on horizontal axes about the same, beams pivoted to said sleeves on vertical axes, connections between the 85 beams and the pole, a seat support mounted to have movement relatively to the frame on both horizontal and vertical axes, connections between the seat support and pole and rigid braces connecting the sleeves and 90 beams.

In testimony whereof I affix my signature in the presence of two witnesses.

CHARLES T. RAY.
